CLAIM

The ornamental design of a location device, as shown and described.

DESCRIPTION

FIG. 1 is a perspective view of a first embodiment of a location device showing our new design;

FIG. 2 is a top plan view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a perspective view of a second embodiment of the location device;

FIG. 8 is a top plan view of FIG. 7;

FIG. 9 is a right side elevation view of FIG. 7, the left side being identical;

FIG. 10 is a front elevation view of FIG. 7; and,

FIG. 11 is an inverted rear elevation view of FIG. 7.
